K. KLEVEN,
ANCHORING APPARATUS FOR SILOS,
APPLICATION FILED APR. 18, 1917.

Patented Aug. 13, 1918.

UNITED STATES PATENT OFFICE.

KNUT KLEVEN, OF MINNEAPOLIS, MINNESOTA.

ANCHORING APPARATUS FOR SILOS.

1,275,268.

Specification of Letters Patent. Patented Aug. 13, 1918.

Application filed April 18, 1917. Serial No. 162,958.

To all whom it may concern:

Be it known that I, KNUT KLEVEN, a citizen of the United States, residing at Minneapolis, in the county of Hennepin and State of Minnesota, have invented a new and useful Anchoring Apparatus for Silos, of which the following is a specification.

This invention relates to apparatus for anchoring stave silos to their foundations, one of the objects of the invention being to provide a simple form of anchoring and bracing apparatus which can be applied readily, easily adjusted, and which will not only hold the silo to its foundation but also reinforce it against the pressure of wind thereagainst.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

In said drawings:

Fig. 1 is an elevation of a portion of a silo having the present improvements combined therewith.

Fig. 2 is a section on line 2-2 Fig. 1.

Fig. 3 is an enlarged section on line 3-3 Fig. 1.

Refering to the figures by characters of reference 1 designates the wall of a silo, preferably formed of staves held together by hoops 2 of the usual or any preferred construction, the silo wall resting on a foundation 3 of concrete. Embedded in this foundation at desired intervals are anchoring strips 4 the lower ends of which are offset, as at 5, to prevent withdrawal from the foundation, while the upper ends of the strips are provided with eyes 6 through which extend the threaded outer ends of tie bolts 7. The threaded inner ends of these bolts are extended through the wall 8 of the silo and are fastened thereto by nuts

as shown particularly in Fig. 3. Mounted on the outer threaded portion of each tie bolt 7 are eyes 9 provided at their lower ends of upwardly diverging brace rods 10 and these eyes 9 are clamped against the eye 6 by nuts 11 engaging the bolt as shown in Fig. 3. The brace rods 10 extend

upwardly desired distances and pass through eyes 12 formed in the ends of straps 13 which are bolted or otherwise secured to the wall of the silo. These straps are arranged above the spaces between the anchoring strips so that one rod 10 extending from one of the anchoring strips will be attached to the same strap 13 as one of the rods 10 connected to the other anchor, as shown particularly in Fig. 1.

It will be apparent that by tightening the nuts 14 which engage the threaded upper ends of the rods 10 the wall of the silo can not only be bound tightly on the foundation but will also be braced against wind pressure from any direction. By having the tie bolts 7 connecting the anchors at the lower ends of the brace rods 10 to the wall of the silo, said wall is securely fastened to the foundation and is prevented from shifting inwardly or outwardly to an undesirable extent from any cause.

It will be noted that each strap 13 is to be extended across several staves and to be fastened to them. Thus all of the staves clapped by each strap are held fixedly together and, when the rods 10 are tightened, all of the staves to which the straps are connected will be clamped tightly onto the foundation, thereby making a rigid structure.

What is claimed is:

The combination with a silo wall formed of staves and a concrete foundation supporting the wall, of anchoring strips having their lower ends offset and embedded in the foundation at points outside of the wall, straps each secured to and extending across a plurality of staves of the wall and having terminal eyes, tie bolts extending horizontally from the wall and adjustably secured to the wall and to the upper ends of

the anchoring strips, and rods having eyes at their lower ends engaged by the tie bolts, the upper ends of the rods being extended into and secured within the terminal eyes in
5 the straps.

In testimony that I claim the foregoing

as my own, I have hereto affixed my signature in the presence of two witnesses.

KNUT KLEVEN.

Witnesses:

ALEX SWANSON,
EDWIN P. NORMAN.
